UNITED STATES PATENT OFFICE.

HARRY S. KELSEY, OF BROOKLINE, MASSACHUSETTS.

SETTLE FOR LUNCH-ROOMS.

1,149,982.

Specification of Letters Patent. Patented Aug. 10, 1915.

Application filed June 1, 1914. Serial No. 842,541.

To all whom it may concern:

Be it known that I, HARRY S. KELSEY, a citizen of the United States of America, and a resident of Brookline, in the county of 5 Norfolk and State of Massachusetts, have invented certain new and useful Improvements in Settles for Lunch-Rooms, of which the following is a specification.

This invention relates to settles, and particularly to settles designed for use in lunch rooms and the like, the particular object of the invention being to economize space and afford more privacy to the customers than is now secured where chairs or tables are used. 15 Another object of the invention is to provide a shelf in the rear of each seat on which the wearing apparel of the customer may be placed while he partakes of his lunch.

A further object of the invention is to 20 provide removable tables which are normally locked to some of the interior partitions and may be removed when it is desired to clean them or replace them with others.

25 The invention consists of a settle provided with a seat separated into a plurality of compartments by a series of partitions extending upwardly from said seat every alternate partition having a forward extension and grooves in its opposite faces to which is adapted to be secured a removable table extending in opposite directions in front of adjacent compartments.

The invention further consists in certain 35 novel features of construction and arrangement of parts which will be fully understood by reference to the description of the drawings and to the claims hereinafter given.

40 Of the drawings, Figure 1 represents a plan of a settle embodying the principles of the present invention. Fig. 2 represents a front elevation of the same. Fig. 3 represents an end view of the same. Fig. 4 represents a sectional detail to be hereinafter referred to. Fig. 5 represents a sectional detail, the cutting plane being on line 5—5 on Fig. 4, and Fig. 6 represents a section through the upper portion of the back and showing the 45 rearwardly extending shelf for supporting the wearing apparel of the customer.

Similar characters designate like parts throughout the several figures of the drawings.

55 In the drawings, 10—10 are end frames

between which are interposed the seat 11 and the back 12. Extending upwardly from the seat 11 are a plurality of partitions 13 and 14, which separate the settle into a plurality of compartments 15, each adapted to be occupied by one person. When seated in one of the compartments a person has considerable privacy as he is hidden by the partitions 13—14 from the occupants of the compartments on each side of him. 65

Extending rearwardly from the upper part of the back 12 is a shelf 16 on which the wearing apparel of a customer may be placed while he is partaking of his lunch. While thus positioned there is little liability of the 70 clothing being soiled, which very often happens in lunch rooms where table-chairs are used and no suitable provision is made for the disposal of the clothing of the customer. The back 12 extends slightly above the shelf 75 16 forming a rib which prevents the clothing from being accidentally displaced.

The partitions 13 each have a forward extension 17 on which is positioned a supporting plate 18 extending to the back 12 and forming ribs 19 on opposite sides of said partitions, this plate forming a support for the table 20. Each table is provided with a bifurcated extension 21, the two arms of which are adapted to be positioned in side 85 grooves 22 formed in opposite side faces of the partitions 13 as shown in Fig. 5. The front part or body portion of each table is of considerable breadth and separated by a rib 23 into two individual parts, each of 90 which is shallowed out as indicated at 24. The body portion of the table extends in opposite directions in front of two adjacent compartments as indicated in Fig. 1. The under side of each table is provided with a 95 socket 25 with which an ordinary latch 26 coacts to lock the table 20 in place and secure it to the extension 17 to which said latch is fastened. It is obvious that these tables 20 will become worn more quickly than the other parts of the settle, and it is contemplated having on hand extra tables which may replace any one of the tables when it is desired to remove one to cleanse, 100 varnish, or stain it. It is also obvious that these removable tables 20 may be made of other material than wood, such as marble, glass, or any similar material readily cleansed, thus making the device more hygienic. 105 110

The settles may be made in any length and have as many compartments as may be desired.

- 5 Ordinarily it is intended to place the settles backed up against the side walls of the lunch room, as is indicated in Fig. 3, but it is obvious that they may be placed back to back in the center of a room, or with their ends abutting the side wall.
- 10 10 Owing to the arrangement of the partitions 13—14 a person in a compartment 15 may eat his lunch in some degree of privacy, as the partition will effectually shut off the occupants of the other booths.

- 15 15 It is believed that the many advantages of this invention will be fully apparent from the foregoing description.

Having thus described my invention, I claim:

- 20 20 1. A settle provided with a partition extending from the back thereof to a point adjacent the front edge of the seat and having horizontal grooves in opposite faces thereof; a horizontal support extending 25 forwardly from said partition; and a detachable table adapted to rest upon said support and provided with parallel groove engaging arms extending to the back of said settle.
- 30 30 2. A settle provided with a partition extending from the back thereof to a point adjacent the front edge of the seat and having horizontal grooves in opposite faces thereof; a horizontal support extending 35 forwardly from said partition; a detachable table adapted to rest upon said sup-

port and provided with parallel groove engaging arms extending to the back of said settle; and locking means secured to said support and engaging the under face of said table.

3. A settle provided with a partition extending from the back thereof to a point adjacent the front edge of the seat and having horizontal grooves in opposite faces 45 thereof; a horizontal support extending forwardly from said partition; ribs on opposite faces of said partition in the same plane with said support; and a detachable table adapted to rest upon said support and provided with parallel groove engaging arms 50 adapted to rest on said ribs.

4. A settle with partitions extending upwardly from the seat and forming a plurality of walled compartments open only at 55 the front and top, each alternate partition being provided with lateral ribs and a support extending forwardly from the front edge of said partition, the upper face of said support being in the same horizontal 60 plane with the upper faces of said ribs; a table adapted to rest upon said support and ribs and having a bifurcated projection adapted to straddle a partition; and means for locking said table in position.

Signed by me at 4 Post Office Sq., Boston, Mass., this 28th day of May 1914.

HARRY S. KELSEY.
